SWITCHING ASSEMBLY

Arthur J. Koda, Morton Grove, Ill., assignor to C. P. Clare & Company, Chicago, Ill., a corporation of Delaware

Filed Feb. 8, 1960, Ser. No. 7,157
13 Claims. (Cl. 200—93)

This invention relates to a switching means and, more particularly, to a new and improved switching means using a sealed switch unit.

In sealed switch units of the type in which a magnetic armature contained in a sealed dielectric envelope is alternately moved from a center-stable position into engagement with a pair of spaced magnetic terminals, the "operate" and "release" current margins of a winding for operating the sealed switch unit are often adjusted by the use of permanent magnetic biasing means. In single-side-stable switch units, a cylindrical permanent magnet is secured to each of the pair of magnetic terminals to extend perpendicularly outward therefrom, and these magnets are then adjusted so that the terminals are biased to opposite polarities by fields of unequal intensity. The magnetic armature is normally held in engagement with one of the terminals by the greater intensity field to provide a "break" contact, and the relative intensities of the fields produced by the two permanent magnets are adjusted to establish the desired "operate" or "release" currents for the winding. However, this biasing arrangement requires the use of two permanent magnets, and the strength and the positioning of these magnets also produces large stray fields that interfere with the "operate" and "release" current adjustments of adjacent switch units in a plurality unit assembly.

This interaction between the stray fields of the sealed switch units in a plural unit assembly is reduced by alternating the polarities of the biasing means for adjacent switch units in the manner shown in detail in the copending application of Arthur J. Koda, Serial No. 787,536, filed January 19, 1959, now Patent No. 3,026,390. However, in applications in which a shielding "can" is not used with the switching assembly and the individual switch units are positioned immediately adjacent each other, as when a plurality of printed circuit relays of the type shown in the copending application of Arthur J. Koda, Serial No. 731,390, filed April 28, 1958, now Patent No. 3,038,976, are mounted adjacent each other, the interaction between the biasing magnets becomes appreciable. Dickten, Jr. Patent No. 2,245,391 discloses a center stable relay that is polarized by a single biasing magnet bridged or disposed between a pair of magnetic terminals. However, this construction cannot be used in single-side-stable relays and does not permit an accurate adjustment of "operate" or "release" currents because the biasing magnet must normally saturate both of the magnetic terminals.

Accordingly, an object of the present invention is to provide a new and improved sealed switch unit.

Another object is to provide a switching assembly in which magnetic interaction between the biasing means for adjacent switch units is prevented.

A further object is to provide a sealed switch unit including new and improved permanent magnetic biasing means.

Another object is to provide a sealed switch unit including a single biasing permanent magnet mounted adjacent one magnetic terminal of the switching unit and spaced from another magnetic terminal thereof.

A further object is to provide a magnetically biased sealed switch unit in which a permanent magnet having a magnetic axis is positioned adjacent one magnetic terminal and extends toward another magnetic terminal with the axis of the permanent magnet forming an acute angle

2

relative to a line passing through the two magnetic terminals.

A further object is to provide a sealed switch unit in which a single biasing magnet longer than the distance between a pair of generally parallel magnetic terminals is positioned with one pole face of the permanent magnet disposed adjacent one magnetic terminal and with an opposite pole face spaced from the other magnetic terminal.

A still further object is to provide a switching assembly in which two parallel magnetic terminals of a sealed switch unit engage opposite sides of a dielectric panel and in which a permanent biasing magnet is disposed adjacent one of the terminals and is spaced from the other of the terminals by the panel.

A further object is to provide a switching assembly including new and improved means for mounting a sealed switch unit and a winding therefor on a printed circuit panel.

In accordance with these and many other objects, an embodiment of the invention comprises a dielectric panel having a plurality of spaced openings and carrying a plurality of discrete electrically conductive layers forming a printed circuit pattern. The sealed switch units that are to be mounted on the printed circuit board each comprise an elongated and generally cylindrical dielectric envelope having a common terminal extending from one end thereof and a pair of spaced and generally parallel magnetic terminals extending from the other end thereof. Each of the dielectric envelopes slidably supports a winding for moving a center stable magnetic armature contained within the envelope into alternate engagement with the inner ends of the pair of magnetic terminals. An assembled switch unit and operating winding is inserted into each of the openings in the printed circuit board so that the engagement of the terminals with the board and the engagement of the winding with the edges of the opening properly locates the winding and switch unit relative to each other and to the board. In this position, one of the magnetic terminals engages one side of the board and the other of the magnetic terminals engages the other side of the board at a location laterally or transversely offset from the one magnetic terminal. One or more of the terminals is suitably secured to the conductive segments to electrically and mechanically connect the switch units to the printed circuit pattern.

In order to provide means for magnetically biasing the center stable armature into normal engagement with one of the magnetic terminals so as to provide a single-side-stable switching construction, each of the sealed switch units is provided with a permanent biasing magnet, preferably rectangular in configuration, that includes a definite magnetic axis terminating at the opposite ends of the magnet in a pair of pole faces of opposite polarity. The length of the magnet measured along its magnetic axis preferably is greater than the spacing between the pair of magnetic terminals. Each of the permanent magnets is mounted with one of the pole faces disposed adjacent one of the magnetic terminals and with its magnetic axis extending generally parallel to the printed circuit panel. In this position, the magnetic axis of the biasing magnet forms an acute angle with a line passing through the two magnetic terminals, and the other pole face is spaced from the other magnetic terminal. The interposition of the printed circuit panel between the magnet and the other magnetic terminal serves to maintain a fixed separation between the other pole face and the other magnetic terminal.

With the biasing magnet arranged in this manner, the inner end of the terminal adjacent the biasing magnet provides a field of greater intensity so that the adjacent end of the center-stable magnetic armature is normally held in engagement with this magnetic terminal. Since

the length of the permanent magnet in the direction of its magnetic axis is preferably greater than the separation between the parallel magnetic terminals and since the other pole face of the biasing magnet is spaced from the other magnetic terminal, the inner end of this other terminal provides a magnetic field of lesser intensity that does not move the armature away from the more strongly biased terminal. By suitably adjusting the magnetic field intensity of the biasing magnet and the separation between the other magnetic terminal and the spaced pole face, the "operate" or "release" current of the switching unit is adjusted to a desired value. Further, by the elimination of one biasing magnet and because of the fact that the stray flux field of the single biasing magnet is reduced in intensity, the magnetic interaction between adjacent switch units on the same printed circuit panel or on adjacent printed circuit panels is substantially eliminated.

Many other objects and advantages of the present invention will become apparent from considering the following detailed description in conjunction with the drawings in which:

FIG. 1 is a top plan view in partial section of a printed circuit relay embodying the present invention which illustrates an assembly of a sealed switch unit and a winding in different manners;

FIG. 2 is a sectional view taken along line 2—2 in FIG. 1;

FIG. 3 is a sectional view taken along line 3—3 in FIG. 1 assuming that a complete switching assembly is shown therein; and

FIG. 4 is a fragmentary perspective view illustrating the relative positions of a biasing magnet and the magnetic terminals of a sealed switch unit.

Referring now more specifically to FIG. 1 of the drawings, therein is shown a switching assembly, indicated generally as 10, which includes a dielectric panel 12 defining a plurality of spaced openings 14 and carrying a printed circuit pattern comprising a plurality of individual conductive segments or layers 16. A sealed switch unit 18 slidably supporting an individual operating winding 20 is disposed in each of the openings 14 with one or more of the terminals of each of the sealed switch units 18 engaging and soldered to portions of the printed circuit pattern. The openings 14 conform to the configurations of the windings 20 and thus serve to locate these windings in a proper position relative to the sealed switch units 18.

In order to provide means for rendering each of the switching units 18 single-side-stable so that a movable armature normally engages one of a pair of magnetic terminals, each of the sealed switch units 18 is provided with a biasing means comprising a single permanent magnet 22. Each of the magnets 22 provides a definite magnetic axis terminating at opposite ends of the magnet 22 in pole faces of opposite polarity. The magnets 22 are mounted on one side of the board or panel 12 with one of the pole faces disposed adjacent one of the magnetic terminals on the switching units 18 and with the magnetic axis extending generally parallel to the dielectric panel 12. Thus, the other pole faces of the magnets 22 are spaced from the other magnetic terminals by intervening portions of the dielectric panel 12. Because of this disposition of the permanent magnets 22, one of the magnetic terminals of each of the sealed switch units 18 is biased with a field of a particular polarity that is of greater intensity so that the armature is normally held in engagement with this terminal while the other terminal is biased to an opposite polarity by a field of lesser intensity. By adjusting the position of the spaced magnetic terminal relative to the permanent magnet 22 and by adjusting the strength of the magnet 22, the "operate" or "release" currents of the windings 20 can be adjusted to a desired value. Further, the stray flux field due to the single biasing magnet 22 associated with each of the switching units 18 is so small that the magnetic interaction between sealed switch units

18 on the panel 12 or between sealed switch units 18 on adjacent panels 12 is prevented.

Referring now more specifically to the dielectric panel or board 12, this panel is formed of any suitable dielectric material and is provided with a printed circuit pattern on one or both sides thereof by any of the methods or processes well known in the art. The printed circuit pattern consists of the plurality of discrete segments or layers 16 of electrically conductive material, such as copper. Most of these segments include an enlarged end portion 16a formed adjacent an edge 12a which provides a male connector for interconnecting the switching assembly 10 with external circuits. The inner ends of most of the segments 16 terminate in enlarged portions 16b or 16c of various configurations that are used to interconnect the components in the switching assembly 10, such as the sealed switching units 18 or the windings 20, with the printed circuit pattern. In the assembly 10 shown in FIG. 1 of the drawings, the enlarged portions 16b are used, for instance, to extend electrical connections to the windings 20, and the enlarged areas 16c are disposed adjacent opposite edges of the elongated openings 14 to provide means for electrically and mechanically interconnecting the switching units 18 with the printed circuit pattern. The dielectric panel 12 also includes a plurality of openings 24 that are used in securing protective layers to the switching assembly 10. The openings 14 are shaped to conform to the general outline of the windings 20 so as to locate these windings on the sealed switch units 18. The lower end of each of the openings 14 (FIGS. 1 and 2) is provided with a narrow opening 26 terminating in a circular opening 28.

The sealed switch units 18 can comprise "dry" type or mercury switch capsules of any of the types well known in the art. In general, each of the sealed switch units 18 includes a sealed dielectric or glass envelope 30 containing a magnetic and movably mounted armature 32 (FIG. 4) that is electrically connected to a terminal or header 34 extending from the lower end of the envelope 30. A pair of generally parallel magnetic terminals 36 and 38 are carried on the upper end of the dielectric envelope 30 opposite the terminal 34. The lower ends of the terminals 36 and 38 are offset inwardly toward each other (FIG. 4) to provide contacts into which the upper end of the armature 32 is alternately moved into engagement under the control of the flux field provided by the winding 20.

Since the magnetic armature 32 is center-stable, i.e., is normally spaced midway between the lower ends of the magnetic terminals 36 and 38, the biasing magnet 22 is provided to render the sealed switching unit 18 single-side-stable. In this condition, the free end of the armature 32 is normally held in engagement with the lower end of the terminal 38 spaced from the terminal 36. When a flux field of a proper orientation is generated by the associated winding 20, the armature is moved out of engagement with the terminal 38, which provides a "break" contact, and into engagement with the lower end of the terminal 36, which provides a "make" contact. The termination of the energization of the related winding 20 permits the armature 32 to be restored to its normal position engaging the terminal pin 38 by the flux field provided by the permanent magnet 22.

To accomplish this, the permanent magnet 22 preferably is formed of a rectangular configuration and is provided with a definite magnetic axis or field orientation such that two pole faces 22a and 22b of opposite polarities are provided at opposite ends of the magnetic axis. The length of the magnet 22 in the direction of the magnetic axis preferably is longer than the distance separating the terminals 36 and 38. To provide a relatively strong flux field of a given polarity adjacent the lower end of the "break" terminal 38, one of the pole faces, such as the face 22a, is disposed immediately ad-

adjacent the outer or upper portion of the magnetic terminal 38, and this magnet is adjusted so that its magnetic axis forms an acute angle with a line passing through the magnetic terminals 36 and 38 transverse to their axes. Because of the angular displacement of the magnetic axis of the magnet 22 and because of the fact that the length of this magnet preferably is greater than the distance between the terminal pins 36 and 38, the second pole face of opposite polarity, such as the pole face 22b, is spaced from the "make" terminal 36. Because of the high reluctance air gap separating the terminal pin 36 from the pole face 22b, the intensity of the field provided by the biasing magnet 22 at the lower end of the terminal 38 is substantially greater than the intensity of the magnetic field of opposite polarity induced at the lower end of the terminal pin 36. The permanent magnet 22 is preferably formed of a material, such as "Alnico V," so that the field of the permanent magnet 22 is concentrated at the pole faces 22a and 22b and there is a minimum leakage flux from the sides of the magnet 22 disposed adjacent the terminal pin 36. It should also be noted that the magnetic terminal 36 provides a lower reluctance path for the flux from the pole face 22b than a path entirely through air in spite of the air gap separating the pole face 22b and the upper portion of the terminal 36 so that the lower end of the terminal 36 is magnetically biased to assume a polarity opposite to that of the lower end of the terminal pin 38. Accordingly, the upper end of the armature 32 is magnetically retained in engagement with the lower end of the magnetic terminal 38 to provide the single-side-stable construction.

When the sealed switch units 18 and the windings 20 are to be mounted on the dielectric panel 12, each of the sealed switch units 18 is inserted into an axial opening 40 in one of the windings 20, and the assembled switch units and windings 20 are then inserted into each of the openings 14 so that the terminal 34 is positioned within the opening 26 with its lower end disposed within the opening 28. At the upper end of the sealed switch unit 18, the terminal 38 is placed in a position resting on the end portion 16c of a conductive segment 16 on one side of the panel 12 while the other magnetic terminal 36 is disposed adjacent the lower or other surface of the panel 12 in a position laterally displaced from alignment with the terminal 38. A single bias magnet 22 is then placed on each of the enlarged end portions 16c adjacent the upper ends of the openings 14 (FIG. 1) with the magnetic axis of the magnet extending generally parallel to the panel 12. The flux field of the permanent magnet 22 holds this magnet in intimate engagement with the magnetic terminal 38 in a proper position in which the side of the magnet 22 is spaced from the magnetic terminal 36 by the intervening dielectric panel 12. In this position, the axis of the terminal pin 36 is intersected by a line extending perpendicular to the magnetic axis of the magnet 22. One or more of the terminals 34, 36 and 38 can then be electrically and mechanically connected to the printed circuit pattern on the dielectric panel 12, as by soldering these terminals to the adjacent portions 16c of the conductive segments 16. In addition, the permanent magnet 22 can be soldered to the terminal pins 38 or the enlarged portions 16c or to both of these elements.

In certain instances, it may be desirable to solder the permanent magnets 22 to the terminal pins 38 before assembling the sealed switch units 18 on the dielectric panel 12. In these instances, the terminal pins 38 and 36 are properly located relative to the magnetic axis of the magnet 22 by the use of a suitable jig. When the assembled sealed switch unit 18 and biasing magnet 22 are positioned on the board 12, the engagement of the side wall of the permanent magnet 22 with the panel 12 aids in properly locating the terminals 36 and 38 relative to the panel 12.

Although the permanent magnets 22 can be magnetized to provide magnetic fields of suitable strength and orientation prior to being mounted adjacent the magnetic terminals 38, this practice may not be desirable because of the possibility of a change in the selected magnetic characteristics during the assembling operation and because of the fact that the sealed switch units 18 may possess different operating characteristics that must be compensated for by providing biasing magnets of different field intensities. Accordingly, it is preferable to mount unmagnetized magnetic material which is to form the permanent magnet 22 in a proper position adjacent the magnetic terminal 38 and to then subject the material to a magnetic field of sufficient strength and orientation that the permanent magnet 22 is provided with a field of proper orientation and greater intensity than is required to bias the sealed switch unit 18 for single-side-stable operation. This magnet is then subjected to an alternating current field which reduces the intensity of its magnetic field. During the application of the alternating current signals, test equipment connected to the sealed switch unit 18 indicates the operating characteristic of the unit 18 so that a desired "release" or "operate" margin can be established. When the desired operating characteristic is established, the application of the alternating current field to the permanent magnet 22 is terminated. Although the intensity of the field of the permanent magnet 22 can be adjusted in the manner described above to control the "operate" and "release" characteristics of the sealed switch unit 18, the angular deflection of the permanent magnet about the axis of the magnetic terminal 38, the length of the permanent magnet 22 in the direction of its magnetic axis, and the consequent spacing of the pole face 22b from the magnetic terminal 36 can also be varied in order to control the operating characteristics of the sealed switch unit 18.

If desired, the windings 20 can be secured in proper positions on the dielectric panel 12 and this panel, the conductive segments 16, and the other components carried on the board 12 can be electrically insulated and protected from the atmosphere by bonding a pair of flexible dielectric sheets 42 and 44 to the opposite sides of the panel 12 in the manner described in detail in the copending application of Arthur J. Koda, Serial No. 848,448, filed October 23, 1959, which application is assigned to the same assignee as the present application. The openings 24 in the printed circuit board 12 are used to facilitate the transmission of the vacuum used in applying the dielectric layers 42 and 44 to the switching assembly 10.

In the normal condition of the switching assembly 10, the biasing magnets 22 magnetically retain the magnetic armatures 32 in engagement with the lower ends of the magnetic terminals 38 so that electrically conductive circuits are completed between the conductive segments 16 connected to the terminals 34 and 38. When an energizing signal is applied to one or more of the windings 20 over the conductive segments 16 connected thereto so as to develop flux fields which induce a polarity in the upper ends of the magnetic armatures 32 that is opposite to the polarity of the lower ends of the terminals 38, the upper ends of the magnetic armatures 32 are repelled from the lower ends of the terminals 38 and are attracted toward the lower ends of the terminals 36 so that the armatures 32 engage the terminals 36 to open the "break" contacts and to close the "make" contacts. When the energization of the coils 20 is terminated and the flux fields collapse, the intensity of the fields induced at the lower ends of the terminals 38 and the resiliency of the armatures transfer the armatures 32 from positions engaging the lower ends of the terminals 36 to ones in which these armatures engage the lower ends of the terminals 38. Thus, the "make" contacts are opened and the "break" contacts are closed, and the

sealed switch units 18 are restored to their normal condition.

Although the present invention has been described with reference to a single illustrative embodiment thereof, it should be understood that numerous other modifications and embodiments can be devised by those skilled in the art that will fall within the spirit and scope of the principles of this invention.

What is claimed and desired to be secured by Letters Patent of the United States is:

1. A switching unit comprising a sealed switch unit having a pair of magnetic terminals carried thereon, a permanent magnet having a pair of spaced pole faces at opposite ends of a magnetic axis, and means mounting said permanent magnet for magnetically biasing the two magnetic terminals with fields of opposite polarity with one of said pole faces adjacent one of said magnetic terminals and with a straight line connecting said pole faces extending generally transverse to said one terminal and outwardly at an acute angle from a line connecting said magnetic terminals so that the other pole face is spaced from the other terminal to apply different degrees of magnetic bias to the two magnetic terminals.

2. A switching unit comprising a dielectric envelope, a pair of generally parallel magnetic terminals spaced from each other by a given distance, a permanent magnet having a pair of pole faces spaced from each other a distance along a magnetic axis of said permanent magnet that is greater than said given distance, and means positioning said permanent magnet for magnetically biasing the two magnetic terminals with fields of opposite polarity with one pole face adjacent one of said terminals and with said magnetic axis extending toward said other terminal at an acute angle relative to a line passing through both of said terminals so that said other pole face is spaced from said other terminal to apply different degrees of magnetic bias to the two magnetic terminals.

3. A switching unit comprising a sealed dielectric envelope, a movable magnetic armature in said envelope, a pair of magnetic terminals carried on said envelope and including a first portion positioned adjacent one end of said armature and a second portion disposed outside of said envelope, said magnetic armature having a portion disposed between the first portions of the pair of magnetic terminals and being free of mechanical stresses sufficient to bias said armature into engagement with either of said magnetic terminals, a permanent magnet having two pole faces positioned at opposite ends of a magnetic axis, and means securing one pole face of said permanent magnet to one of said second portions with said magnetic axis extending generally transverse to said one second portion and forming an acute angle with a line passing through both of said second portions, said other pole face of said permanent magnet being spaced from said other second portion, the two terminals being magnetically biased by said magnet with fields of opposite polarity.

4. A switching unit comprising a sealed dielectric envelope, a pair of magnetic terminals carried on said envelope and extending along a pair of spaced parallel lines, a magnetic armature contained within said envelope and including a portion disposed between and movable relative to said magnetic terminals, said magnetic armature being free of mechanical stresses sufficient to bias said portion into engagement with either of said pair of magnetic terminals, a permanent magnet having a pair of pole faces connected by a magnetic axis, and means mounting said permanent magnet for magnetically biasing the two magnetic terminals with fields of opposite polarity with one pole face adjacent one of said magnetic terminals and spaced from the other of said magnetic terminals, said permanent magnet being mounted in a position in which said magnetic axis extends generally transverse to the axis of said one magnetic terminal and

in which a line perpendicular to said magnetic axis intersects the axis of said other magnetic terminal.

5. A switching assembly comprising a dielectric panel having an opening, a sealed switch unit having a pair of spaced magnetic terminals, means mounting said switch unit in said opening with the terminals disposed on opposite sides of said panel, a permanent magnet having a pair of opposite pole faces at opposite ends of a magnetic axis, and means mounting said permanent magnet on said panel for magnetically biasing the two magnetic terminals with fields of opposite polarity with one of said pole faces adjacent one of said terminals and with said magnetic axis extending substantially parallel to said panel.

15 6. A switching assembly comprising a dielectric panel having an opening therein and at least one electrically conductive layer disposed adjacent an edge of said opening, a sealed switch unit having at least a pair of spaced magnetic terminals at one end thereof, said sealed switch unit being positioned in said opening with one of said terminals secured to said layer on one side of said panel and with the other terminal positioned on the other side of said panel, and a permanent magnet mounted adjacent one of said terminals and spaced from the other of said terminals by said panel, with the two terminals magnetically biased by said magnet with fields of opposite polarity.

7. A switching assembly comprising a dielectric panel having an opening therein and at least one electrically conductive layer on at least one side of said panel disposed adjacent an edge of said opening, a sealed switch unit having a pair of magnetic terminals at one end thereof, said sealed switch unit being disposed in said opening with one of said terminals engaging said layer on one side of said panel and the other of said terminals positioned on the other side of said panel spaced laterally from said one terminal, means connecting said one terminal to said layer, and a permanent magnet mounted on said one side of said panel adjacent said one terminal and extending over said other terminal but spaced therefrom by said panel, with the two terminals magnetically biased by said magnet with fields of opposite polarity.

8. A switching assembly comprising a dielectric panel having an opening, a sealed switch unit having a pair of generally parallel and spaced magnetic terminals, said sealed switch unit being mounted in said opening with one of said terminals positioned on one side of said panel and the other of said terminals positioned on the other side of said panel, a permanent magnet having a pair of pole faces connected by a magnetic axis, and means mounting said permanent magnet on said panel for magnetically biasing the two magnetic terminals with fields of opposite polarity with one of said pole faces adjacent one of said terminals and so that a line perpendicular to said magnetic axis intersects the other of said terminals.

9. A switching assembly comprising a dielectric panel having a plurality of spaced openings, a plurality of electrically conductive layers secured to spaced portions of said panel and including portions disposed adjacent said openings, a plurality of sealed switch units each comprising a dielectric envelope having at least two spaced terminals, each of said switch units being disposed in one of said openings with the terminals secured to said portions, and a winding disposed in each of said openings and carried on the dielectric envelope of the sealed switch unit, said openings generally conforming to the configuration of the windings to locate said windings in proper positions on said sealed switch units.

10. A switching assembly comprising a dielectric panel having a plurality of spaced openings, a plurality of electrically conductive layers secured to spaced portions of said panel and including portions disposed adjacent said openings, a plurality of sealed switch units each comprising a dielectric envelope having at least two spaced

magnetic terminals projecting from one end of said envelope, permanent magnetic means secured to one of each pair of said terminals and disposed adjacent but spaced from the other one of the terminals in each pair thereof to magnetically bias the two terminals of each pair with fields of opposite polarity, each of said switch units being disposed in one of said openings with at least one of the terminals secured to one of said portions, and a winding disposed in each of said openings and carried on the dielectric envelope of the sealed switch unit, said openings generally conforming to the configuration of the windings to locate said windings in proper positions on said sealed switch units.

11. The switching assembly set forth in claim 10 including a dielectric material covering each side of said panel to electrically and mechanically protect said switching assembly and to electrically insulate said permanent magnetic means.

12. A switching assembly comprising a sealed and elongated dielectric envelope, a pair of magnetic terminals carried on one end of said envelope and each including a first portion disposed within the envelope and a second portion projecting out of said envelope, said second portions extending generally parallel to each other and being spaced from each other a given distance, a movable magnetic armature supported from the other end of said envelope and having a portion disposed between the first portions of the pair of magnetic terminals, said magnetic armature being free of mechanical stress sufficient to bias said armature into engagement with either of said magnetic terminals, permanent magnet means having two pole faces of opposite polarity positioned at opposite ends of a magnetic axis, the length of said permanent magnet means along a straight line connecting the pole faces being greater than said given distance, and means securing one pole face of said permanent magnet means adjacent one of said second portions with said straight line extending transverse to said one second portion and forming an acute angle with a line passing through both of said second portions so that the other pole face of 40 said permanent magnet means is spaced from said other

second portion, the two terminals being magnetically biased by said magnet with fields of opposite polarity.

13. A switching assembly comprising a dielectric panel having an elongated opening therein, at least one electrically conductive layer having a portion disposed adjacent one end of said opening, a sealed switch unit including a pair of spaced magnetic terminals at one end thereof, said sealed switch being disposed in said opening with said pair of magnetic terminals disposed with at least one of said pair of magnetic terminals disposed adjacent said portion of the electrically conductive layer, means connecting said one magnetic terminal to the adjacent portion of the electrically conductive layer, and permanent magnet means for biasing the two terminals of said pair with fields of opposite polarity and including a pair of opposite pole faces disposed at opposite ends of a magnetic axis, the length of said permanent magnet means in the direction of said magnetic axis being greater than the distance between said pair of magnetic terminals, said permanent magnet means being connected to one of the magnetic terminals with one of the pole faces adjacent this terminal and with the other pole face spaced from the other magnetic terminal, the magnetic axis of said permanent magnet means extending generally transverse to the connected one of the magnetic terminals and forming an acute angle with the plane passing through the pair of magnetic terminals.
